UNITED STATES PATENT OFFICE.

THEODORE M. LANE, OF LOCKE, NEW YORK.

WASHING-MACHINE.

SPECIFICATION forming part of Letters Patent No. 244,464, dated July 19, 1881.

Application filed May 18, 1881. (Model.)

To all whom it may concern:

Be it known that I, THEODORE M. LANE, a citizen of the United States, residing at Locke, in the county of Cayuga and State of New York, have invented certain new and useful Improvements in Washing-Machines; and I do hereby declare that the following is a full, clear, and exact description of the same, reference being had to the annexed drawings, 10 making a part of this specification, and to the letters and figures of reference marked thereon.

Figure 1 of the drawings is a cross-section of my invention, and Fig. 2 is a perspective view of the cylinder disconnected from the 15 boiler.

The present invention has relation to that class of washing-machines consisting of a cylinder supported within a boiler or other vessel to contain the soap and water, the clothes 20 to be washed being placed within the cylinder and the latter revolved, the soapsuds or water circulating through the same while in motion. In order to produce a rubbing action on the clothes during the rotation of the cylinder, the 25 periphery thereof was fluted or formed of longitudinal corrugations, the water being admitted through suitable perforations or holes. These corrugations or flutes being of metal and so small and numerous, they would produce 30 too great a friction upon the clothes, which would tend to wear them, especially where the fabric is of a fine and delicate texture, also twist and wind them up, so that it would require a greater length of time to perfectly wash 35 the clothes and an increased supply of water. These cylinders have also been constructed in the form of a cage, or, in other words, an open cylinder or drum formed by connecting a series of angular or other formed bars to suitable heads, said bars being connected some distance apart, and running parallel with each other and horizontally around the rim or periphery of the heads. These open cylinders, 40 as above referred to, allow the clothes to come in contact with too much water, which lessens the agitating effect upon them during the rotation of the cylinder, the clothes becoming 45 too wet and heavy.

The object of my invention is to remove the 50 objections above referred to by producing a cylinder of a particular form upon its exterior and interior, whereby the most delicate fabric

can be thoroughly and perfectly washed without injuring it, and requiring but a small quantity of water in the boiler. These objects I attain 55 by the construction substantially as shown in the drawings and hereinafter described.

In the accompanying drawings, A represents the boiler, of sheet metal, within which is supported the cylinder B, constructed wholly of 60 wood. The cylinder B consists of two star-shaped heads, C, to which are connected longitudinal sections a of wood. These sections a, which are simply flat boards, I prefer to secure to the edges of the heads by suitable 65 screws, so that if one of the sections should become broken it can be removed and a perfect one secured in its place, or should either head become injured and worthless a new one can be substituted, as all the sections are 70 detachably connected to the heads. The cylinder B is provided with a cover, D, which is suitably hinged to the main portion of the cylinder and fastened by any convenient means. The cylinder B has openings b running the entire length thereof. These openings are at the apex of the angle formed by the two slats connected to the opposite edges of the points of the star-shaped heads C, so that it will allow 75 one to wash with much less water than were 80 the openings between the star-points, which not only economizes in the use of soap, but requires less time to heat the water, as the quantity is much smaller, and saves labor in rotating the cylinder, as the greater the depth of 85 the water the harder the cylinder will be to turn.

By reference to Fig. 1 of the drawings it will be seen that there is but a small quantity of water required of sufficient depth to simply touch the apex of the angle when the cylinder is in position, as illustrated. When the cylinder is turned the apex of the angle will come a sufficient distance below the surface of the water to take up the quantity needed and 90 deposit it in a sheet over the clothes. The interior form of the cylinder, which is like that of the exterior, agitates the clothes sufficiently to thoroughly wash them without twisting them up or wearing them, while at the same 95 time they are kept wet just sufficiently to render the clothes easily cleaned.

The boiler, which may be provided with suitable handles, has interior concave sides, c, to

prevent the water from splashing over the sides of the boiler, as would be the case were the sides vertical.

The heads C, at each end of the cylinder, are provided with suitable journals for resting in bearings in the ends of the boiler A, and a suitable crank-handle for turning the cylinder. These, however, forming no part of my invention, may be constructed in any manner desired.

Having now fully described my invention, what I claim as new, and desire to secure by Letters Patent, is—

A cylinder for washing-machines, consisting

of the star-shaped heads C, having detachably connected thereto sections *a*, with openings *b* extending the entire length of the cylinder, said sections serving to form the inner rubbing-surface of the cylinder, substantially as and for the purpose set forth.

In testimony that I claim the above I have hereunto subscribed my name in the presence of two witnesses.

THEODORE M. LANE.
